UNITED STATES PATENT OFFICE.

ANDREW JACKSON PICKARD AND GEORGE MELSON, OF EUGENE CITY, OREGON, ASSIGNEES OF ONE-HALF TO JOHN STRAUB AND WILLIAM I. VAWTER, BOTH OF SAME PLACE.

CAR-COUPING.

SPECIFICATION forming part of Letters Patent No. 392,968, dated November 13, 1888.

Application filed April 19, 1888. Serial No. 271,136. (No model.)

To all whom it may concern:

Be it known that we, ANDREW JACKSON PICKARD and GEORGE MELSON, citizens of the United States, residing at Eugene City, in the county of Lane and State of Oregon, have invented new and useful Improvements in Car-Couplings, of which the following is a specification.

Our invention relates to improvements in car-couplings; and it consists in certain novel features, hereinafter described and claimed.

Figure 1 of the drawings is a side elevation of our improved coupling. Fig. 2 is a vertical longitudinal section of the same. Fig. 3 is a perspective view of the link detached. Fig. 4 is a perspective view of the link-follower detached.

Referring to the drawings by letter, A designates the draw-bar of a car, and B the recessed draw-head attached thereto, which draw-head is provided with the upper and lower coupling-pin holes, b b', respectively, and the mouth b², having the inwardly-converging top, bottom, and sides to direct the entering link. The recess b³ on the inner side of the mouth is rectangular. The link C has its ends c flattened on their outer edges, for a purpose hereinafter explained. D is the coupling-pin, having the rounded point d, as shown. E is the link-follower, rectangular in shape, and situated within the rectangular recess b³. The said follower has the flat-bottomed transverse groove e in its front end, the vertical opening e' at a proper point of its length, and the stem e² projecting from its inner end. F is a pin resting in the opening e' and falling by gravity when the follower is pushed in into the recess f in the floor of the recess b³, which recess f has the inner inclined side, f', and the outer vertical side or shoulder, f², against which the outer side of the pin F abuts and retains the

follower within the draw-head against the action of the spiral spring G, which surrounds the stem e² of the follower, and the inner end of which bears against the end of the recess b³ or 45 against the block g, inserted therein.

It is evident that the spiral springs in the opposite draw-heads will prevent the link having any loose motion.

The squared outer edge of the end of the 50 link rests in the flat-bottomed groove in the outer end of the corresponding follower, the pressure of which, caused by the spring in rear thereof, holds the link against the pin inside its bend and keeps it horizontal. 55

Before coupling, the point of the coupling-pin rests on the top of the follower, and when the latter is driven inward by the entering link the pin falls through the link and couples the draw-heads. 60

Having described our invention, we claim—
The herein-described car-coupling, comprising the draw-head having a recess, f, in its floor, provided with a vertical shoulder, f², at its front end and with an inclined rear end, f', 65 the follower having a vertical opening, e, near its rear end and provided in its front end with the transverse flat-bottomed groove e, the pin F, playing freely in the vertical opening e' and having its lower end resting in the recess f, 70 and the coupling-link having flat ends adapted to engage in the flat-bottomed groove e, substantially as specified.

In testimony that we claim the foregoing as our own we have hereto affixed our signatures 75 in presence of two witnesses.

ANDREW JACKSON PICKARD.
GEORGE MELSON.
